UNITED STATES PATENT OFFICE.

NATHAN LANES, OF NEW YORK, N. Y.

LOCK.

Application filed July 2, 1927. Serial No. 202,984.

The object of the present invention is to provide an auxiliary lock for doors and the like which is designed, more particularly, to reinforce and strengthen the ordinary locks now in commercial use and prevent the use of master keys from a point exterior the door, and also resist the prying apart of the bolt keeper and the bolt casing. Further objects will be hereinafter set forth.

10 The invention will be understood by reference to the accompanying drawings in which—

Figure 1 is a plan view of an embodiment of the invention in position on a door and door jamb, and

Figure 2 is a front elevation of the same;

Figure 3 is a detail perspective view of certain of the elements illustrated in the preceding figures;

20 Figure 4 is a view illustrating chain holding means for application to the device of the succeeding figure;

Figure 5 is a front elevation of a modified form of locking means;

25 Figure 6 is a plan view of the device illustrated in Figure 5;

Figure 7 is a plan view of a device similar to that of Figure 5 but adapted for use with round knurled lock releasing knobs;

30 Figure 8 is an elevation, partly in section, of the device illustrated in Figure 7;

Figure 9 is an end elevation of the device illustrated in the preceding figure;

35 Figure 10 is a sectional end elevation showing the application of the chain holding means illustrated in Figure 4;

Figure 11 is a plan view, in partial section, of modified means embodying the principle of the preceding figures but attached to 40 the lock bolt, the section being on the line 11—11, Figure 12, and

Figure 12 is a view in elevation of the device illustrated in the preceding figure.

Referring to the drawings, 1 illustrates 45 the bolt casing of a lock and 2 the bolt keeper, the casing being attached to a door 3 and the keeper to a door jamb 4 by any suitable means, as by the screws 5. The construction of the bolt throwing mechanism forms no 50 part of the present invention and is not shown in detail, except that an oval thumb-piece 6 is shown, the thumb-piece leading to the bolt operating mechanism for throwing the bolt into and out of the keeper 2.

55 Pivottally mounted upon screw 7 is a latching arm comprising two members each hav-

ing a serrated face section *a*, the two being held in mutual engagement by a short bolt 8 engaged by a nut 9. Screw 7 passes through keeper 2 into the door jamb 4 and, intermediate the head 7* of the screw and the latching arm, may abut a sleeve 7** on the screw.

Referring to Figures 2 and 3 it will be seen that one section of the latching arm is formed with a longitudinal slot *b* to enable adjustment. At the right hand end the latching arm is formed with any suitable means to engage the thumb-piece 6. In the present instance such means comprises side flanges 11 and a top flange 12 for fitting over the thumb-piece rearwardly thereof. Fixed upon the bolt keeper 2 is a spring catch 13 which lies over the upper edge of the latching arm and prevents a thin instrument from being inserted from the front of the door and employed to raise the latching arm. When it is desired to raise the latching arm, a slight pressure upon the spring catch will enable the swinging of the arm upwardly to release the lock handle or thumb-piece 6.

If desired, a chain holder 14, Figure 2, may be placed on screw 7, the chain leading to a ring 15 having one section of a size to slip over the thumb-piece 6 and a smaller upper section to fit the rounded shank of the thumb-piece. Or, if desired, the chain may be formed as in Figure 4 wherein the ring 15* has at its end a flat disk 16 to fit within an opening of the same size in the thumb-piece such as that shown at 17, Figures 5 and 10. By moving the disk downwardly into the lower portion of a channel communicating with said opening 17, the chain is securely held by the overhanging walls of the channel which are spaced a distance only equivalent to the shank 16* rearwardly of the disk 16.

In Figures 5 and 6 the latching arm 19 is sectional as in the preceding figures and the bolt which engages the two sections is also employed as a pivoting member for securing the latching arm to the bolt casing 1. The left hand end of the latching arm is formed as a hook to engage a headed stud 20 secured to the bolt keeper 2. If desired, a spring 21 may be employed on the screw 22 or bolt (Figure 6) on which the latching arm is mounted, and the flanges 11 and 12 may embrace the thumb-piece per se rather than its shank as in the preceding figures. When the flanges are designed to engage the shank, the

latter should be square or oval in form as will be understood without further explanation.

In the form shown in Figure 5 a spring catch 23 is employed below the swinging arm 5 to serve in the same manner as the spring catch 13 of Figures 1 and 2.

The device illustrated in Figures 7, 8 and 9 is substantially similar to that shown in Figures 5 and 6 with the exception that the latching arm 24 is formed in one piece and is provided with means for engaging the serrated or toothed edge of a round thumb-piece 25. The arm 24 is pivotally mounted at 26, is normally engaged by a spring catch 27 and its free end is adapted to engage a headed stud 28 carried by the bolt keeper 29. At its right hand end latching arm 24 is formed with a lateral apertured projection 30, the aperture being substantially the diameter of the toothed thumb-piece 25, and its walls being preferably toothed as at 31 to engage the tooth of the thumb-piece for holding the latter against rotation from a point exterior the door, as by a master key.

In Figures 11 and 12 I have shown means connected directly to the bolt of the lock whereby the bolt may be latched by means independent of its normal actuating means. The bolt casing 32 is formed in its front wall 30 with a slot 33 through which projects a post 34 connected to the bolt 35. Pivotally mounted upon the reduced end of the post is a latching arm 36, it being held in place by a screw 37. The left hand end of latching arm 36 is hooked to enter an opening vertically formed in the receiving member 38, which member is secured to the bolt keeper 39 in any suitable manner. A spring catch 40 may be secured to the bolt casing upon latching arm 36, it serving the same function as the spring catch 13 illustrated in Figures 1 and 2 and previously described. In the operation of the said device, throwing of the bolt 35 into the keeper 39 by means of the thumb-piece 41 will move post 34 to the left sufficiently to enable latching arm 36 to be swung into position to engage the receiving member 38 and spring catch 40 will spring over the upper edge of the latching arm to prevent upward movement except when the catch is pressed backwardly.

It will be understood that various modifications may be made in the form and arrangement of the elements is illustrated in the drawings without departing from the spirit of the invention, it being understood that means are provided for supporting the latching arm in upright and disengaged position, such means in the embodiments illustrated in the drawing being the springs 10, 10^x or the 60 spring catch members 13, 23, 27, 40.

What I claim and desire to secure by Letters Patent is as follows:

1. In devices of the character described, a latching arm adapted to be connected to the bolt mechanism of a lock and a device adapted to be secured to the jamb of a door for receiving one end of said arm whereby the bolt is held against movement and is latched to the jamb.

2. In combination, a lock casing, bolt mechanism including a bolt carried by said casing, a bolt keeper adapted to be secured to the jamb of a door, and a swinging arm adapted to be thrown into action to simultaneously engage said bolt mechanism and said keeper to hold the bolt against movement and hold the bolt casing and keeper together, as and for the purpose described.

3. A device constructed in accordance with claim 2 in which the arm is sectional and adjustable.

4. A device constructed in accordance with claim 2 in which the arm is formed at one end with means for engaging a bolt throwing thumb-piece to hold the latter against rotation, the opposite end of the arm being adapted for securing to the bolt keeper.

5. A device constructed in accordance with claim 2 in combination with spring means for holding the arm in disengaged position.

6. Auxiliary locking means for door locks, a bolt throwing mechanism including a shaft having a thumb-piece and the like comprising a latching arm, means for pivotally supporting the arm and for securing it to the jamb of a door, and means carried by the arm adapted to engage the bolt throwing thumb-piece to prevent movement of the latter.

In testimony whereof, I have signed my name to this specification.

NATHAN LANES.
